UNITED STATES PATENT OFFICE.

FERDINAND W. KROGH, OF SAN FRANCISCO, CALIFORNIA.

CENTRIFUGAL PUMP.

1,277,430.

Specification of Letters Patent. Patented Sept. 3, 1918.

Application filed August 30, 1915. Serial No. 47,980.

To all whom it may concern:

Be it known that I, FERDINAND W. KROGH, of San Francisco, California, have invented certain new and useful Improvements in Centrifugal Pumps, whereof the following is a specification.

This invention relates to centrifugal pumps, and more particularly to means for packing the pump shaft, and its object is 10 chiefly to provide simple and effective means for packing the pump shaft at points of difficult accessibility. Other objects of the invention will appear hereinafter.

The invention is more particularly applicable to gang pumps, and I will describe it as applied to such.

In carrying out the invention, as applied to gang pumps, I proceed as follows:—I arrange two or more pumps in the well, and 20 at least one pump near the top of the well, and I apply the balancing devices to the latter. I provide a tubular casing around the shaft, in the well, and within the discharge pipe, which casing is perforated at 25 points between shaft bearings, so that the pressure of the water in the discharge pipe is communicated to the packings at those points, and thus keeps them tight. The casing also serves another function, to wit: to convey waste oil from the bearings to a point of discharge, and prevent it from contaminating the pumped water.

In the accompanying two sheets of drawings I have illustrated the invention as applied to a gang pump having two pumps in the well and one pump at the top of the well, the latter being of sufficient size to contain balancing means for the entire system.

40 In the drawings:—

Figure 1 is a central vertical section of the well and pump system therein.

Fig. 2 is a similar section, on an enlarged scale, of a portion of the apparatus, showing 45 two bearings and the perforations in the shaft casing.

Figs. 3, 4 and 5 are similar sections showing portions of the apparatus at different stages of operation.

In these figures:—

1 represents the well, shown in Fig. 1 only. 2 and 3 are pumps therein arranged in series taking their suction through the pipe 4 and discharging through the pipe 5,

into the surface pump 6, which in its turn discharges at the point 7.

The surface pump comprises the casing 8 and the impeller 9. The impeller takes water at the point 10, and throws it outward in the usual manner into the peripheral 60 chamber 11. The casing also comprises a chamber 12, under the impeller which receives water under pressure from the discharge and thus supports the weight of the various moving parts. 13 is a chamber in 65 the casing above the impeller into which water may enter by leakage through the joints and from which it is thrown by the passages 14, shown in dotted lines when the impeller moves downward in the casing, 70 thus creating more or less of a vacuum in the chamber 13, so that the impeller rises again in the casing. Thus the parts are balanced.

At the top of the casing 8 of the surface 75 pump is an oil cup, 8^a, surrounding the shaft and serving to receive a supply of oil for the latter.

15 is the shaft common to all pumps. This shaft is provided with the usual bearings and their packings at 16 and 17 which are accessible points and also with other bearings 18 and 19 down in the well and therefore of difficult accessibility.

20 is a casing surrounding the shaft 15, 85 and extending from the lower pumps upward to the bearing 17. This casing is perforated as seen at 21, at a point between the bearings 18 and 19, so that the packing is subjected to a pressure due to the hydrostatic head in the discharge pipe. Thus the packing is compressed upon the shaft to form a tight bearing and prevent the oil from running down and leaking out through the various joints into the well and at the 90 same time the packing above the perforation forms a filter to keep the water in the casing 20, clear of sand.

The bearings may be supplied with oil by means of an oil feed pipe 22, extending down 100 into the well and provided with branches as shown leading to the bearings. The oil as it works through the bearings is received in the casing 20, and works upward therein to the waste oil discharge 23. Thus the oil 105 is prevented from contaminating the water in the well and in the discharge pipe, so that the pumps supply pure water.

24 is a cock or valve, shown in Fig. 1, upon the oil discharge 23, by which it may be choked to determine the pressure within the shaft casing 20.

5 Referring to Figs. 3, 4 and 5; Fig. 3 illustrates a stage just after the starting of the pumps when the discharge pipe is not yet full of water and the waste oil 25, shows just above the bearing 18. In the Fig. 4, 10 the pumping has advanced a little; the water is higher in the discharge pipe and the waste oil has been pushed up by water entering the shaft casing through the perforations 21. In Fig. 5, the apparatus is in full 15 operation, the water fills the discharge pipe and the waste oil 25, is at the top of the shaft casing and flowing out through the discharge 23.

For the purpose of holding the packing 20 down upon the bearing 19 and compressing it, I provide a weight 26, which rests upon the packing. In the Figs. 3, 4 and 5, the weight is shown in different positions as it works downward in use.

25 The bearing 18, and any other intermediate bearings that may be used, is provided with a channel 27 to provide a free rise of the waste oil and water in the casing 20.

The surface pump is secured to fixed supports by the flanges and bolts at 28, as shown 30 in Fig. 1, applied to its casing. The lower pump casings are hung to the discharge pipe 5, which hangs from the casing 8 of the surface pump, and constitutes the suction 35 thereof.

Having thus described my invention, and an embodiment of it, in the full, clear and exact terms required by law, and knowing that it comprises novel, useful and valuable 40 improvements in the art to which it pertains, I here state that I do not wish to be limited to the precise construction and arrangement of the several parts, as herein set forth, as the same may be variously modified by a skilled mechanic without departing 45 from the spirit of the invention.

What I claim and desire to secure by Letters Patent of the United States, is the following, to wit:—

50

Claims.

1. A pumping apparatus, having bearings of difficult accessibility, a casing surrounding the pump shaft between said bearings

adapted to receive wasted oil, provided with 55 perforations, packing in said casing forming a tight bearing to prevent thereby the oil from leaking out into the well, and forming at the same time a filter to keep the water entering said casing, through said perforations, clear of sand.

2. A pumping apparatus, provided with bearings of difficult accessibility, an oil feed for said bearings, a casing surrounding the pump shaft adapted to receive the waste oil 65 from said bearings and to discharge the same, packing in said casing and means to compress said packing.

3. A pumping apparatus, provided with bearings of difficult accessibility, an oil feed 70 for said bearings, a casing surrounding the pump shaft and adapted to receive the waste oil from said bearings and a waste oil discharge and means to prevent the oil from running down and leaking out through the 75 various joints of said casing.

4. A pumping apparatus, provided with bearings of difficult accessibility, means to oil said bearings, a casing surrounding the pump shaft, having packing therein, and adapted to receive waste oil from said bearings, an outlet at the upper end of said casing and perforations at its lower end, whereby the hydrostatic pressure in the discharge acts through said packing and forces the 85 waste oil to the outlet.

5. A pumping apparatus, provided with bearings of difficult accessibility, an oil feed for said bearings, a casing surrounding the pump shaft provided with perforations at 90 its lower portion, a controllable discharge outlet at its upper portion, said casing adapted to receive the waste oil from said bearings, the intermediate bearings being channeled to permit the free passage of 95 the water from said perforations to said controllable discharge outlet, carrying therewith the waste oil and packing in said casing to prevent the oil from running down and leaking out through the various joints of the 100 casing.

In testimony that I claim the foregoing I have hereto set my hand this 25th day of August, 1915, in the presence of witnesses.

FERDINAND W. KROGH.
